DESIGN FOR A CASING FOR DOOR CLOSING
AND CHECKING DEVICE OR SIMILAR
ARTICLE

Louis F. Schmidt, Chicago, Ill., assignor to Norton Lasier Company, Chicago, Ill., a corporation of Illinois

Application June 20, 1938, Serial No. 77,942

Term of patent 7 years

To all whom it may concern:

Be it known that I, Louis F. Schmidt, a citizen of the United States, residing in Chicago, in the county of Cook and State of Illinois, have invented a new, original, and ornamental Design for a Casing for Door Closing and Checking Device or Similar Article, of which the following is a specification, reference being had to the accompanying drawing forming part thereof:

In said drawing—

Figure 1 is a perspective view of a casing showing my new design; and Figure 2 is a top plan view of the casing shown in Figure 1.

The back of the casing of this design, which is not shown, is plain. The casing has the same appearance when seen from the opposite perspective view. The medial transverse lines of deformation is a characteristic feature of this design.

I claim:

The ornamental design for a casing for door closing and checking device or similar article, substantially as shown and described.

LOUIS F. SCHMIDT.
